[57] ABSTRACT

A foundry molding machine providing both an anvil jolt and a shockless jolt during squeeze which includes a ram projecting through the squeeze piston, such ram serving as a stationary stem cooperating with the table to obtain an anvil jolt and floating on the squeeze pressure during squeeze to obtain a shockless jolt.

25 Claims, 6 Drawing Figures

SHEET 1 OF 4

This technical drawing shows an exploded view of a mechanical assembly, possibly a pump or valve. The components are labeled with numbers 10 through 32. Key parts include a top cap 12, a central shaft 14, a housing 16, a circular component 18, a piston 20, a rod 21, a base 22, a side cover 28, and a bottom housing 30. A small detail 26 is shown separately at the bottom left. The assembly is shown in an exploded state, allowing a view of the internal parts and their relative positions.

JOLT-SQUEEZE MOLDING MACHINE

This invention relates generally as indicated to a jolt-squeeze molding machine and more particularly to a simplified machine obtaining both an anvil jolt and a shockless jolt during squeeze providing molds of uniform high density and hardness.

Many foundry people consider that optimum ramming of molding sand in the production of foundry molds can be obtained by jolting a mold in the conventional anvil jolt manner, i.e. wherein the shock is absorbed by the base of the machine, and then squeezing the mold against a squeeze head while simultaneously applying a shockless jolt to the mold, or a jolt wherein the shock is not absorbed by the base of the machine. The standard anvil jolt apparently rams the deep pockets more effectively than can be done with shockless jolt, and a shockless jolt ram apparently helps to obtain maximum overall hardness of the mold.

It is accordingly a principal object of the present invention to obtain a simplified foundry molding machine providing both anvil jolt and shockless jolt during squeeze.

Another principal object is the provision of such machine which will obtain a more effective shockless jolt during squeeze.

A further important object is the provision of such machine which avoids the use of operating or compensating springs which may require replacement.

Another object is the provision of such machine having a ram which projects through the squeeze piston and into the squeeze chamber, the latter thus serving as an air spring to rebound the ram against the underside of the table.

A further object is the provision of such machine wherein the ram in its inoperative position serves as a stationary stem cooperating with the underside of the table to form an air chamber, alternate pressurization and venting of which obtains an anvil jolt.

Still another object is the provision of such machine wherein the squeeze pressure is varied in synchronism with the jolt to obtain a more effective overall hardness of the mold.

A yet further object is the provision of such machine wherein the ram during shockless jolt projects into the squeeze chamber and pressure at the top of the ram will drive it downwardly and when such pressure is vented, the squeeze pressure will cause the ram to rebound against the underside of the table.

A still further object is to provide such a jolt molding machine having a pivotally mounted pair of arms facilitating mold box turnover.

Other objects and advantages of the present invention will become apparent as the following description proceeds.

To the accomplishment of the foregoing and related ends, the invention, then, comprises the features hereinafter fully described, the following description and the annexed drawings setting forth in detail certain illustrative embodiments of the invention, these being indicative, however, of but a few of the various ways in which the principles of the invention may be employed.

In said annexed drawings:

FIG. 1 is a side elevation of a machine in accordance with the present invention;

FIG. 2 is a partial rear elevation of the machine of FIG. 1 illustrating the mounting of the rollover arms and actuator;

FIG. 3 is a top plan view of such machine with the squeeze head removed;

FIG. 4 is an enlarged fragmentary vertical section taken in the plane of FIG. 1 showing the table jolt and squeeze mechanism;

FIG. 5 is a vertical section of another slightly modified machine in accordance with the present invention illustrating the table down, the mold filled and in position for anvil jolt; and

FIG. 6 is a view similar to FIG. 1 illustrating such machine with the table up during squeeze and during shockless jolt.

Referring first to FIGS. 1 through 3, it will be seen that the illustrated machine includes a generally upstanding frame 10,

5 to the forward lower end of which is secured table housing or base 11. The upper end of the frame 10 supports head 12 for horizontal swinging movement on the axis of pin 13. Such head 12 supports a downwardly projecting squeeze board 14 which is generally vertically aligned in its operative position with table 15 supported for vertical movement in the table housing or base 11. The squeeze head 14 can accordingly be swung out of the way to permit overhead filling of mold box 16 supported on table 15 with molding sand.

10 The mold box 16 may be of the type including cope and drag flasks 17 and 18, respectively, with a pattern or matchplate 19 therebetween. Such flasks forming the mold box may include oppositely projecting trunnions as indicated at 20 which are adapted to be engaged by cradles 21 on the distal ends of arms 22 and 23, the proximal ends of such arms being secured by clamps 24 to the squared projecting ends of shaft 25 journaled at 26 to the back of the upstanding frame 10.

20 To lift the mold box from the table 15, the arms 22 and 23 are pivoted upwardly to engage the mold box trunnions and such pivoting is obtained by piston-cylinder assembly 28, the rod of which is connected at 29 to arm 30 secured to shaft 25. The blind end of such piston-cylinder assembly is pivotally connected at 31 to the frame 10. Extension of the piston-cylinder assembly 28 will thus pivot the arms 22 and 23 upwardly lifting the mold box until the trunnions obtain the position seen generally at 32 so that the operator may then easily invert the mold box.

25 Referring now additionally to FIG. 4, it will be seen that the table 15 includes a depending cylindrical extension 40 which fits within the upstanding cylindrical portion 41 of squeeze piston 42. The squeeze piston 42 includes a pair of piston rings 43 riding against the interior cylindrical surface 44 of upstanding cylindrical portion 45 of the table housing or base 11. The top edge of the cylindrical portion 41 of the squeeze piston 42 includes a lip 46 which overlies the top peripheral edge of the cylindrical extension 45 of the housing or base 11. Such lip includes an annular flat surface 47 supporting the table 15 in its lowermost position.

30 A guide pin 49 mounted in the upstanding cylindrical portion 45 of the base 11 projects into slot 50 in the upstanding cylindrical portion 41 of the squeeze piston 42, such pin and slot maintaining the squeeze piston against rotation within its cylinder and also limiting its vertical movement. A guide pin 51 mounted in the upstanding cylindrical portion 41 of the squeeze piston projects into slot 52 in the depending cylindrical portion 40 of the table 15, such pin and slot connection likewise maintaining the table 15 against rotation and limiting its vertical movement. In addition to the pin and slot connections aforesaid, the table 15 may be provided with a jolt guide pin 54 extending through jolt guide bushing 55. Such guide bushing is mounted in extension 56 extending from the lip 46 of the upstanding cylindrical portion 41 of the squeeze piston 42 and also in knuckle 57 extending from the upstanding cylindrical portion 45 of the base 11.

35 A ram guide bushing 60 is mounted in a central aperture 61 in the squeeze piston 42 and is secured in position by the fasteners 62 as indicated. An O-ring seal 63 is provided between the squeeze piston and such bushing. A sliding seal 64 is provided in such ram guide bushing riding against cylindrical downward extension 65 of jolt ram 66. The larger diameter portion of the jolt ram 66 slides within the cylindrical inner surface of the depending cylindrical portion 40 of the table 15. A Teflon or like piston ring 67 is provided as indicated between the appropriate sliding surfaces. It is noted that the axial extension of the sliding surfaces is minimized to avoid cocking problems.

40 Such sliding surfaces are also provided with lubricating passages as indicated at 68 and 69. The upper end of the jolt ram 66 is provided with an upstanding cylindrical center projection 70 which in the lowermost position of the table has a slight clearance indicated at 71 with the downwardly extending projection 72 on the underside of the table. In such lower-

most position of the table, the ram 66 through its lower cylindrical reduced diameter extension 65 is bottomed on the base 11 as indicated at 73. The extension 65 of the jolt ram 66 thus projects through the squeeze piston 42 into squeeze chamber 75 beneath such piston.

An intermediate chamber 76 is provided between the enlarged portion of the jolt ram and the top of the squeeze piston, such chamber also underlying the depending cylindrical extension 40 of the table 15. Such chamber 76 is connected to atmosphere through passage 77 extending through cylindrical extension 40.

A third chamber 78 is provided between the top of the ram 66 and the underside of the table 15. The volume of the chambers 78, 76 and 75 as well as the weight of the moving parts is carefully determined to obtain the desired operation of the machine.

In operation, the table 15 may support either the combined cope and drag flask mold box structure with the matchplate therebetween or a single flask with a pattern plate supported on the table. After the mold box has been filled with sand, to obtain a conventional or anvil jolt, air at plant or line pressure (about 80 p.s.i.) enters the jolt chamber 78 above the ram 66 through passage 79. The pressure in chamber 78 elevates the jolt table 15 until exhaust ports 80 are uncovered. Such exhaust ports communicate with vertical grooves 81 in the exterior of the cylindrical depending extension 40 of the table 15, such grooves communicating with ports 82 and vertical passages 83 in the upwardly extending cylindrical portion 41 of the squeeze piston to exhaust to atmosphere through radially extending passages 84.

When such exhaust ports 80 are uncovered by vertical elevation of the table, the table drops and strikes the annular top surface 47 of the lip 46 of the squeeze piston 42 which is bottomed on the upstanding cylindrical portion 45 of the base 11. This anvil or conventional jolt may continue as desired to obtain suitable ramming of the sand within the flask. It will be appreciated that the extension 70 on the jolt ram 66 may be slightly extended so that the anvil jolt is obtained on such extension to provide a center strike through the ram bottomed on the base 11 at 73.

During squeeze, air under pressure is admitted to the squeeze chamber 75 and the squeeze piston 42 moves upwardly carrying with it the table 15. The squeeze board 14 telescopes within the top of the flask or mold box pressing the sand against the pattern. The ram 66 also moves upwardly and is held in contact with the underside of the jolt table closing the clearance 71. This movement of the ram is obtained by the squeeze pressure acting on the underside of the ram extension 65 which is exposed to the squeeze pressure in squeeze chamber 75 beneath the piston 42.

Jolt during squeeze is obtained by again introducing line pressure (80 p.s.i.) through jolt line 79 into jolt chamber 78. This pushes the ram 66 downwardly until air exhausts through the exhaust passages 80, 81, 82, 83 and 84. When exhaust occurs, the squeeze pressure in chamber 75 acting on the underside of the extension 65 causes the ram to move upwardly striking the underside of the jolt table in the center at the extension 72. Such shockless jolt during squeeze may continue until the mold has obtained its desired maximum overall hardness.

Even though the chamber 76 is vented to atmosphere through the passage 77, downward movement of the ram 66 during such shockless jolt during squeeze will nonetheless compress the air in chamber 76 because of the restricted size of the vent passages and such compressed air will assist in driving the ram back against the underside of the table. It is noted that the area of the ram 66 exposed to the chamber 78 is considerably greater than the area of the extension 65 exposed to the squeeze chamber 75. Thus equal pressures in such chamber will cause the ram to move downwardly. It will, of course, be appreciated that such areas may vary depending on the pressures and pressure mediums employed.

After the mold is rammed, the table is lowered and the pattern may be drawn from the mold. When using the cope and drag flask with a matchplate therebetween, the piston-cylinder assembly 28 may now be extended elevating such mold box so that the operator may invert the same and upon retraction of the piston-cylinder assembly 28 the box may then be placed on the table inverted. The drag half of the mold box may now be filled with sand and the operation repeated.

Referring now to FIG. 6, the illustrated machine includes a housing or base 100 which includes a bottom 111 and an upstanding cylindrical portion 112. Fitted within such cylindrical portion is a squeeze piston 113 provided with piston rings seen at 114 and 115. Such squeeze piston includes an upstanding cylindrical portion 116 projecting slightly above the top edge of the cylindrical portion 112 of the housing in the lowermost position of such squeeze piston.

A jolt table 120 includes a depending cylindrical extension 121 which fits within the upstanding cylindrical portion 116 of the squeeze piston. Mounted within such depending cylindrical extension 121 of the table 120 is ram 122. A ram follower 123 of reduced diameter is provided subjacent the underside of the ram 122. Such ram follower need not be physically connected to the ram. The ram is provided with a depending annular skirt 124 making the ram substantially coextensive with the cylindrical extension 121 of the table 120 in the FIG. 5 position.

The ram follower projects downwardly through annular boss 126 in the squeeze piston 113, the top of which is provided with packing retainer 127 secured thereto by fasteners 128. A piston ring 129 is provided in such retainer riding against the ram follower 123.

The table 120 is provided with one or more downwardly projecting guide pins 130 projecting through bushings 131 in bosses 132 projecting from the housing 110. The lower ends of such guide pins are provided with stop nuts indicated at 133 which limit the upward movement of the table 120 with respect to the housing 110. In this embodiment, the maximum stroke of the table may, for example, be approximately 7-1/4 inches. This, of course, may vary depending upon the type and size of machine with which the present invention is employed.

The table 120 supports pattern plate 140 on which is provided pattern 141. The pattern plate in turn supports flask 142 which is filled with molding sand 143 from an overhead hopper, not shown. To fill the mold box formed by the flask and pattern plate with the sand 143, squeeze head 144 is moved out of the way, such squeeze head being mounted on head 145 cantilevered over the mold box from upstanding frame 146 in the back of the machine, as in the FIG. 1 embodiment.

The ram is provided with a plurality of lubrication passages indicated at 150 and lubrication passages 151 are also provided through the cylindrical portion 112 of the housing 110. The chamber 152 between the ram and the top of the piston 113 is connected to atmosphere through passages 153. Such passages terminate on the underside of the table 120 as indicated at 154 with the horizontal branches being closed by plugs 155.

The chamber 160 between the top of the ram and the underside of the table can be pressurized through jolt air passage 161. Exhaust ports 162 are provided in the depending cylindrical extension 121 of the table 120 and communicate with vertical passages 163 in such extension which in turn communicate with passages 164 in the cylindrical extension 116 of the squeeze piston 113. The ram 122 is provided with a teflon or like material piston ring as indicated at 165 adjacent the top edge thereof. Passage 166 is provided in the housing 110 communicating with squeeze chamber 167 beneath squeeze piston 113, such chamber including recess 168 extending beneath ram follower 123 in the position shown in FIG. 1.

The description of the operation now follows. With the flask 142 positioned on the pattern plate 140 on the table 120 and filled with sand 143, to obtain conventional or anvil jolt, air at plant or line pressure (about 80 p.s.i.) enters the jolt cavity

160 above ram 122 through passage 161. The pressure in chamber 160 lifts table 120 until exhaust ports 162 are opened. The jolt air pressure now exhausts through the passages 162, 163 and 164 exhausting adjacent the top of the cylindrical extension 116 of the piston 113. On exhaust, the jolt table drops and strikes the top annular surface of the extension 116 of squeeze piston 113 as indicated at 170. The squeeze piston 113 is during the anvil or conventional jolt bottomed in the housing as shown at 171 in FIG. 1. The ram 122 is also bottomed in such housing through follower 123 and the downward force on the ram resulting from the pressure in jolt chamber 160 is accepted through the ram 122 and the follower 123 which is in contact with the housing bottom 11. This anvil jolt may be repeated as desired.

To obtain the strike on the top of the cylindrical extension 116 of the squeeze piston 113 as seen at 170, there is provided a slight clearance seen at 172 between the top of the ram 122 and the underside of the table 120. If desired, the dimension of the follower and ram may be slightly extended to obtain during the anvil jolt a strike at the opposed surfaces indicated by such clearance.

Now referring to FIG. 6, during squeeze air under pressure is admitted to the squeeze chamber 167 through port 166 and the squeeze piston 113 moves upwardly carrying with it the table 120. The squeeze head 144 telescopes within the top of the flask pressing the sand against the pattern. The ram 122 also moves upwardly and is held in contact with the underside of the jolt table as indicated at 173 by the squeeze pressure acting on the bottom surface 174 of the ram follower 123 which is exposed to the squeeze pressure in the squeeze chamber 167 beneath the piston 113.

Jolt during squeeze is obtained by introducing line pressure (80 p.s.i.) through jolt line 161 into jolt chamber 160. This pushes ram 122 downwardly until air exhausts through exhaust passages 162, 163 and 164 exiting at the top of the cylindrical extension 116 of the squeeze piston 113. When exhaust occurs the squeeze pressure in chamber 167 acting on the underside 174 of the ram follower 123 causes the ram to move upwardly striking the underside of the jolt table at 173. As in the FIG. 4 embodiment, the ram is also assisted by pressure in chamber 152 even though such chamber is vented. Such shockless jolt during squeeze may continue until the mold has obtained its desired maximum overall hardness.

It is noted that as the jolt pressure in the chamber 160 drives the ram 122 and follower 123 downwardly, the latter projects into the squeeze chamber 167 accordingly reducing its volume and increasing slightly the squeeze pressure. As the follower is driven out of the chamber 167 by the pressure therein, the squeeze pressure is reduced. The squeeze pressure thus pulsates or varies with the shockless jolt strike occurring at the dip or minimum pressure in such pulsations. Maximum squeeze pressure is obtained between jolt strikes. The slight reduction in squeeze pressure during the jolt strike is believed to permit the sand to move better obtaining more compactness and thus obtaining the desired maximum overall hardness of the mold.

The volume of the cavities 160 and 167 as well as the weights of the moving parts again must be carefully determined to obtain the desired action.

After the mold is rammed, the table is lowered and the pattern 141 is drawn from the mold.

I, therefore, particularly point out and distinctly claim as my invention:

1. A foundry molding machine having a squeeze table, and a squeeze piston supporting said table, wherein the improvement comprises a ram extending through said piston to enable both anvil or shockless jolt, said ram floating on the squeeze pressure to obtain shockless jolt during squeeze.

2. A foundry molding machine as set forth in claim 1 including a cylindrical extension on said piston of said assembly and a cylindrical extension on said table, said table extension being telescoped into said piston extension.

3. A foundry molding machine as set forth in claim 2 wherein said table extension and the upper end of said ram form a jolt cavity, the end of said ram exposed to such cavity being larger in area than the end exposed to such squeeze pressure.

4. A foundry molding machine as set forth in claim 3 including an exhaust port in said table extension operative to vent such cavity as pressure therein relatively moves said ram and table.

5. A foundry molding machine as set forth in claim 4 including a second cavity formed by said ram and piston-cylinder assembly between said first cavity and said piston, and means operative to maintain said second cavity vented.

6. A foundry molding machine as set forth in claim 5 wherein said table extension extends into said second cavity, said last mentioned means being a vent passage in said table extension.

7. A foundry molding machine as set forth in claim 1 including a cylindrical extension on said table, said ram being mounted for reciprocation in said table extension.

8. A foundry molding machine as set forth in claim 7 wherein said ram includes a cylindrical extension of reduced diameter projecting through said piston.

9. A foundry molding machine as set forth in claim 8 including an extension on said piston supporting said table in one position thereof, said ram and its extension being bottomed on the cylinder of said piston-cylinder assembly and slightly clearing said table whereby air pressure between said ram and table will elevate the latter to drop the same on said piston extension when said pressure is vented to obtain an anvil jolt.

10. A foundry molding machine as set forth in claim 1 wherein said ram is bottomed on said cylinder of said piston-cylinder assembly and clears said table in the lowermost position thereof, whereby air pressure between said ram and table will elevate said table and drop the same on venting of such pressure to obtain an anvil jolt.

11. A foundry molding machine as set forth in claim 1 including a pair of arms operative to swing adjacent said table to facilitate lifting of a mold box therefrom.

12. A foundry molding machine having an upstanding cylindrical housing, a table adapted to support a sand filled flask, and a piston in said housing supporting said table for vertical movement, the improvement comprising a jolt ram cooperating with said table and extending through said piston to enable both anvil or shockless jolt, said ram being exposed to the pressure beneath said piston.

13. A foundry molding machine as set forth in claim 12 including a cylindrical extension on said piston thus supporting said table.

14. A foundry molding machine as set forth in claim 13 including a cylindrical extension on said table telescoping over said ram and forming therewith a jolt cavity on top of said ram.

15. A foundry molding machine as set forth in claim 14 wherein both said piston and said ram are bottomed on said housing when there is no pressure beneath said piston whereby pressurization and venting of such cavity will elevate said table and then drop the same to provide an anvil jolt.

16. A foundry molding machine as set forth in claim 15 wherein said ram clears said table when bottomed on said housing so that said table strikes the top annular edge of the cylindrical extension on said piston to provide such anvil jolt.

17. A foundry molding machine as set forth in claim 16 wherein said ram includes an extension of reduced diameter extending through said piston.

18. A foundry molding machine as set forth in claim 12 including a pair of pivotally mounted arms adapted to lift such sand filled flask from said table to facilitate inversion.

19. A jolt-squeeze molding machine capable of producing an anvil or shockless jolt comprising a squeeze piston, jolt means, a table, said squeeze piston supporting said table for movement toward and away from a squeeze head, said jolt means comprising a ram operative to strike said table, said

ram including an extension projecting through said squeeze piston and into the pressure side chamber of said piston.

20. A jolt-squeeze molding machine as set forth in claim 19 including a cylindrical extension on said piston supporting said table, and a housing in which said piston is mounted for movement.

21. A molding machine as set forth in claim 20 wherein both said squeeze piston and said ram are bottomed on said housing in the lowermost position of said table.

22. A molding machine as set forth in claim 21 including a cylindrical extension on said table cooperating with said jolt ram to form a jolt cavity above said ram, and means to pressurize said cavity to elevate said table and vent said cavity to drop said table to obtain an anvil jolt.

23. A jolt-squeeze molding machine comprising a frame, a vertically movable table in said frame adapted to support a

sand filled mold box, an overhead squeeze head, a jolt mechanism in said table capable of jolting the sand in such mold box prior to and during elevation of the latter against said head, a pair of arms operative to lift such mold box from said table to facilitate inversion, said jolt mechanism including means to provide an anvil jolt prior to elevation and a shockless jolt during elevation.

24. A jolt-squeeze molding machine as set forth in claim 23 wherein said jolt mechanism includes a ram stationary for said anvil jolt and movable for said shockless jolt.

25. A jolt-squeeze molding machine as set forth in claim 24 including an expandible squeeze pressure chamber operative to elevate said table, said ram floating on said squeeze pressure therein during shockless jolt.
